[57] CLAIM

The ornamental design for a combined umbrella and light, as shown and described.

DESCRIPTION

FIG. 1 is a front, top and side perspective view of the combined umbrella and light showing my new design in the open condition;

FIG. 2 is a front elevational view thereof, the rear being a mirror image of the front shown in FIG. 2 with the exception of the switch;

FIG. 3 is a side elevational view thereof, the side opposite being a mirror image of the side shown in FIG. 3;

FIG. 4 is a top plan view thereof;

FIG. 5 is a bottom plan view thereof;

FIG. 6 is a front elevational view thereof in a partially collapsed condition with a container being shown in perspective; and,

FIG. 7 is a perspective view thereof in the collapsed condition.

FIG.1.

FIG. 3.

FIG. 2.

FIG. 5.

FIG. 4.

FIG. 7.

FIG. 6.
